(57) **CLAIM**

The ornamental design for a thermal accessory for footwear, as shown and described.

DESCRIPTION

FIG. 1 is a perspective view of a thermal accessory for footwear showing my new design, shown in a position of use on an environmental ski boot;

FIG. 2 is a front view of the thermal accessory shown in FIG. 1;

FIG. 3 is a first side view of the thermal accessory shown in FIG. 1 with the cover strips shown in position;

FIG. 4 is a second side view of the thermal accessory shown in FIG. 1 with the cover strips shown in position;

FIG. 5 is a top view of the thermal accessory shown in FIG. 1 with the cover strips shown in position;

FIG. 6 is rear view of the thermal accessory shown in FIG. 1 with the cover strips shown in position; and,

FIG. 7 is a bottom view of the thermal accessory shown in FIG. 1 with the cover strips shown in position.

The uneven broken lines, showing the ski boot in the various drawing figures, are for environmental purposes only and form no part of the claimed design.
